UNITED STATES PATENT OFFICE.

ISIDOR KITSEE, OF PHILADELPHIA, PENNSYLVANIA.

ELECTRIC TRANSMISSION OF INTELLIGENCE.

No. 317,821.

Specification of Letters Patent.

Patented April 17, 1906.

Application filed June 24, 1904. Renewed December 26, 1905. Serial No. 293,327.

To all whom it may concern:

Be it known that I, ISIDOR KITSEE, of the city and county of Philadelphia, State of Pennsylvania, have invented certain new and useful Improvements in the Electric Transmission of Intelligence, of which the following is a specification.

My invention relates to an improvement in electric transmission, and has more special reference to the improvement of telephonic circuits. Its object is to increase the efficiency of the telephonic line of transmission.

The line of transmission as employed by me consists of a series of sections, each section consisting of a pair of insulated conductors twisted together, one conductor of the preceding section being intertwined with one conductor of the section following.

Referring to the drawings, Figure 1 and Fig. 2 illustrate my invention in diagrammatic views.

A is the line of transmission as an entirety, of which A' A² A³ A⁴ are separate sections. The section A', designed to form one terminal 25 of the line, comprises the short wire a and the long wire a'. The section A² comprises part of the wire A' and part of the wire a'. The section A³ comprises part of the wire a² and part of the wire a³, and the section A⁴ comprises part of the wire a³ and the short wire a⁴, which forms the other terminal of said line.

B and B' are the two telephonic stations.

The operation in this line is apparent. Impulses generated in the secondary of the inductorium at the station B will flow through the wire a, will induce impulses in a', whereby impulses will be induced in a², and thereby in a³ and a⁴, and from a⁴ the impulses will flow to the receiving device and ground at station B'. So, also, will the impulses generated at the station B', through the inductive influence of one section of the twisted wire upon the other section, be received in the proper manner through the receiving device at station B.

Having now described my invention, what I claim as new, and desire to secure by Letters Patent, is—

1. A line of transmission consisting of a series of sections of a pair of twisted wires, one wire of the first section in operative relation to a receiving device at one station, the second wire of said section in inductive relation to one wire of the third section, the second 55 wire of said third section in inductive relation to a receiving device of the second station,

the terminals of the line being connected through instruments to a return-conductor.

2. In combination with two telephonic stations more or less remote from each other a line of transmission connecting both stations inductively with each other, said line of transmission consisting of a series of conductively independent sections, each section consisting of two wires twisted around each other, the different sections in inductive relation to each other through the twist of one wire of one section around one wire of the section following, the terminals of the line being connected through instruments to a return-conductor.

3. In electricity, a line of transmission connecting two stations with each other, said line of transmission consisting of a series of independent pairs of conductors, each of said pairs of conductors overspanning only part of the space between said two stations, the different pairs in inductive relation with each other through the intertwining of one conductor of one pair with one conductor of the other pair, the terminals of the line being connected through instruments to a return-conductor.

4. A composite sectional line conductor comprising a plurality of sections, each section consisting of conductively-independent conductors twisted together, one of said conductors being common to neighboring sections.

5. A composite sectional line conductor comprising a plurality of sections, each section consisting of conductively-independent conductors twisted together, one of said conductors being common to neighboring sections and the conductors of neighboring sections twisted with said common conductor being conductively independent from each other.

6. A composite sectional line conductor comprising a plurality of sections, each section consisting of conductively-independent conductors twisted together, neighboring sections being conductively connected as to one of the twisted conductors, and alternate sections being conductively independent from each other as to all conductors.

7. A composite sectional line conductor comprising a plurality of sections, each section consisting of conductively-independent conductors twisted together, a conductor of each section being in twisted relation with a conductor of neighboring section.

8. A composite sectional line conductor comprising a plurality of sections, each section consisting of conductively-independent conductors twisted together, each conductor being in twisted relation with conductively-independent conductors of neighboring sections.

9. In a system for transmission of varying electric currents of impulses, transmitting and receiving apparatus, and a composite sectional line conductor inductively joining the transmitting and receiving apparatus, said line conductor comprising a plurality of

sections each section consisting of conductively-independent conductors twisted together, each conductor being in twisted relation with conductively-independent conductors of neighboring sections.

In testimony whereof I hereby sign my name, in the presence of two subscribing witnesses, this 22d day of June, A. D. 1904.

ISIDOR KITSEE.
